UNITED STATES PATENT OFFICE.

JAMES H. REED, OF SWAMPSCOTT, MASSACHUSETTS, ASSIGNOR TO HAMEL SHOE MACHINERY COMPANY, A CORPORATION OF MASSACHUSETTS.

SOLE-SKIVING MACHINE.

1,368,572.

Specification of Letters Patent. Patented Feb. 15, 1921.

Application filed February 24, 1919. Serial No. 278,799.

To all whom it may concern:

Be it known that I, JAMES H. REED, a citizen of the United States, residing at Swampscott, in the county of Essex and State of 5 Massachusetts, have invented certain new and useful Improvements in Sole-Skiving Machines, of which the following is a specification, reference being had therein to the accompanying drawings.

10 In the manufacture of shoes, it is often desired to make a shoe of a size somewhat longer than sole blanks on hand, and in order to use the shorter blanks, the so-called "dutching process" is employed. In this 15 process the blank is skived through at its rear portion on a long scarf, and the scarf having been cemented the parts are moved relative to each other, and then pressed together to form a blank of a size longer than 20 the original.

This invention seeks to provide a machine for skiving the blanks for this purpose to produce a long, even scarf in an expeditious manner, and in which the skived portions 25 will leave the machine convenient to the operator so that the portions of each blank may be re-associated to form the longer blank with a minimum of time and effort. For this purpose the machine is arranged so 30 that the rear end of the blank is pushed into the machine from the front by the operator into contact with a gage, and during the skiving the blank is fed in the reverse direction toward the operator so that both 35 parts of the severed blank leave the machine in convenient relationship to each other and to the hands of the operator.

This invention also provides means whereby the proper placing of stock in position 40 serves to initiate the actuating mechanism to perform the skiving operation.

Further objects and advantageous details of construction will appear from a more complete description of embodiments of the 45 invention disclosed in the accompanying drawings in which,—

Figure 1 is a plan view of the machine;

Fig. 2 is a cross section thereof through its center;

50 Fig. 3 is a right end elevation, the driving pulley being removed;

Fig. 4 is a diagrammatic view showing the action of the feed wheels;

55 Fig. 5 is a detail view showing the clutch mechanism;

Fig. 6 is a detail perspective showing the sole blank as skived and lengthened according to the "dutching process,"

Fig. 7 is a diagrammatic view similar to Fig. 4, but illustrating a modified form of 60 the lower roll;

Fig. 8 is a fragmentary plan view showing an automatic clutch mechanism; and

Figs. 9 and 10 are detail views of this 65 same mechanism.

A represents the machine head for supporting the operative mechanism, which is suitably carried on a work bench or similar support. An upstanding bracket B at each end of the machine carries bearings for 70 an actuating shaft C and a shaft D above and parallel thereto. Loosely carried on shaft C is a sleeve 1, having at each end thereof forwardly extending arms 2, 2^a. Similar arms 3, 3^a are carried on the ends 75 of a sleeve 4 loosely carried by the shaft D. Arms 3 and 3^a are provided with alined bearings 5, 5^a at their free ends for a shaft 6 which carries rigid therewith, between the arms 3 and 3^a, the feed roll 7. Arms 2, 2^a 80 carry in a similar manner a coöperating feed roll 8 on shaft 8'. Arms 3 and 3^a are provided with slots 9, 9^a, in which extend the upper ends 10 and 10^a of rods 11 and 11^a, these upper ends being journaled on 85 cams 12 (only one being shown) fixed to a shaft 13 mounted in bearings in arms 3, 3^a. At one end shaft 13 carries a lever 14, and at the other a fastening nut 15. Rods 11, 11^a project downwardly through the 90 arms 2, 2^a and into the base of the machine where they pass through lugs 16, 16^a, their positions therein being adjustable by means of nuts 17, 18; 17^a, 18^a. Surrounding rods 11, 11^a between the arms 2 and 3, and 2^a and 95 3^a are suitable coil springs 19, 19^a. Similar springs 20, 20^a bear on the under side of arms 2, 2^a and on the upper side of nuts 21.

Carried also by arms 2, 2^a and extending across the machine is a plate 22 which is 100 carried on the bracket 23, preferably integral with the arms 2, 2^a. Rearwardly of plate 22 is an adjustable plate 24 mounted on bracket 23 by a pin 25 passing through slot 26 in the bracket. Plate 24 has an adjustable gage 26 having a work contact element 27 at its forward end.

Shaft C carries a pinion 28 fixed thereon meshing with a gear 29 mounted on a shaft 8'. At the other end of shaft C is a pinion 110

30 which meshes with a similar pinion 31 on shaft D. Pinion 31 meshes with a gear 32 carried by shaft 6, and of the same size as gear 29. Belt pulley E is loosely carried on shaft C and has projecting from the hub thereof a lug 33. A collar 34 is fixed on shaft C and has a recess 35 therein to slidably support a pin 36. A coil spring 37 housed within a recess in collar 34 serves 10 to project pin 36 through recess 35 so that its end may be contacted by the lug 33. Mounted on a stub shaft 38 beneath shaft C is a sleeve 39, carrying integral therewith a cam arm 40 and a latch-carrying arm 41. 15 Arm 41 has fast thereto a latch 42 having a beveled end 43, which may be thrust between a portion of collar 34 and a head 44 on pin 36 to retract it against the tension of spring 37 out of the path of lug 33. Arm 41 also 20 carries a connection 41' to a suitable treadle mechanism. A coil spring 45 surrounding sleeve 39 normally urges the latch member 43 into engagement with head 44.

Loosely carried by shaft 8' is a collar 46 25 having a cam 47 integral therewith at its outer end. Collar and cam 46, 47 are resiliently held to rotate with shaft 8' by means of a coil spring 48 bearing at one end against cam 47 and at the other against 30 an adjustable collar 49 carried by pin 50 having a nut 51 thereon by which the compression of spring 48 may be regulated. Arm 40 carries a pin 52 at its free end which engages the circumference of cam 47. 35 A stationary knife 53 is carried in front of the machine in a horizontal plane having a cutting edge 54 opposite the space between feed rolls 7 and 8. Knife 53 is adjustable by means of square-headed bolts 55, 55^a 40 working in suitable slots therein, and may also be provided, if desired, with adjusting screws 56, 56'. In Fig. 4 it is seen that the feed roll 7 is of special form, having a cut-away portion from c to a; a spiral gripping 45 portion of constantly increasing size from a to b; and a substantially concentric portion b—c.

The operation of the device above described is as follows: A sole to be scarfed is 50 inserted from the front of the machine while it is stationary, at which time the cut-away portion c—a of roll 7 is downward, thus allowing the stock to be freely inserted between rolls 7 and 8, the stock being inserted until it touches the contact element 27 of the gage 25. The operator then 55 depresses the treadle, withdrawing the latch 42 from behind the head 44 of pin 36, which is immediately projected by spring 37 into 60 the path of lug 33. As soon as lug 33 contacts therewith, shaft C begins to rotate, and through the meshing gears and pinions the feed rolls 7, 8 rotate in a direction to force the work parallel to the knife toward the 65 operator. Cam 47 holds the latch retracted

during the several revolutions of shaft C required to complete one revolution of the feed rolls, whereupon if the treadle is released the machine stops. As the point a on roll 7 strikes the work the feed motion begins, and as roll 7 continues to rotate the stock is pressed down farther and farther until the point b is reached. The upper surface of the stock is then on a level with or below the knife edge 54, the springs 19, 19^a; 70 20, 20^a allowing roll 8 to be depressed, besides allowing rolls 7 and 8 to accommodate themselves to the various thicknesses of work.

It is thus seen that as the feed begins, the 80 knife 53 starts to cut from the lower face of the material, and when the point b is reached the stock has been forced against the edge of the knife and in a direction transverse of the direction of feed until the knife 85 emerges from the upper surface, thus skiving the sole on a long scarf into two portions. The feed portion b—c of roll 7 insures that the stock is fed completely out of the machine even when the scarf terminates 90 before the end of the stock is reached. The forward scarfed portion is fed out above the knife, and the rear portion is fed out below the knife, both convenient to the operator's hands, so that they may be reassembled and 95 put in a convenient position to be stuck together again with the parts somewhat separated as shown in Fig. 6 to make the blank of a size longer than the original. Rocking of lever 14 serves to adjust the height of roll 7, in addition to the adjustment affected by nuts 17 and 18.

In Fig. 7 a modified construction is shown wherein the lower roll 8^a is of similar form to the roll 7, and so requires no depression 105 against the tension of the springs, as the cutting progresses through the stock, the configuration of the roll itself allowing for the change in elevation thereof.

A modified construction is shown in Figs. 110 8, 9 and 10 in which the proper positioning of the work in the machine serves to actuate the clutch mechanism without the necessity of depressing the treadle. In this modification the plate 26 carries thereon an adjustable plate 60 in place of the adjustable gage 25. Plate 60 carries a slidable gage 61 normally urged forward by a spring 62 engaging between lugs 63 and 64 on the gage and plate respectively. A bell crank lever 65 is 115 pivoted on plate 60, the arm 66 of which engages a pin 67 carried by gage 61, so that the sliding of the gage 61 will rock bell crank lever 65. The other arm of this bell crank lever is pivoted to a link 68, which in turn is 120 pivoted to a rod 69 slidably mounted in a guide 70 carried by the frame of the machine. At its outer end rod 69 carries a trip member 71 which may rotate to a limited extent thereon. Trip 71 carries an abutment 125 130

72 adapted to be urged into contact with a similar abutment 73 fixed to rod 69 by means of a coil spring 74, one end of which engages trip 71, and the other end of which 5 is fast to a collar 75 fixed on rod 69. Drive wheel E carries the contacting lug 33 as before, and is also provided with a lug 76. Sleeve 39 carries the latch member 42, which actuates the sliding pin 36 as before de- 10 scribed and also carries an arm 77 having an upwardly turned end 78 in the same plane transverse of the shaft as lug 76. Trip 71 is normally held out of this plane by means of spring 62, but on pressure of stock against 15 gage 61 thereby rocking bell crank lever 65, rod 69 will be projected to the right, thus bringing trip member 71 into this plane. It is seen therefore, that if stock placed in the machine is pushed against the gage 61, mem- 20 ber 71 coming between the lug 76 and part 78, will be contacted by lug 76 on the rotation of drive wheel E, and will rock member 71 outwardly pushing on extension 78 and rocking arm 77 downwardly which, through 25 sleeve 39, will serve to retract the latch 42 from behind pin 36 and the machine will start as before described. As the rolls grip the stock, it is fed away from the gage 61, which immediately returns to its former po- 30 sition, retracting member 71 out of the plane of lug 76, whereupon the mechanism will stop after one revolution of the feed rolls.

Having thus described certain embodiments of my invention, though it is evident 35 that many changes might be made without departing from the spirit or scope thereof, what is claimed is,—

1. In a skiving machine, a pair of feed rolls, and a skiving knife mounted with its 40 edge adjacent to the bite of said rolls, one of said rolls having a cut-away portion to admit of stock being inserted freely between said rolls and a spiral gripping surface whereby said stock may be forced against 45 and across said knife edge.

2. In a skiving machine, a pair of feed rolls, a skiving knife mounted with its edge adjacent to the bite of the rolls, one of said rolls having a cut-away portion to admit of 50 stock being inserted freely between said rolls, and a back gage for determining the extent of admission of stock between said rolls, said rolls being arranged to feed stock against said knife edge and away from said 55 gage.

3. In a skiving machine, a pair of feed rolls, a skiving knife mounted with its edge adjacent to the bite of said rolls on one side thereof, and a back gage opposite the bite of 60 said rolls on the other side thereof, one of said rolls having a cut-away portion to admit of stock being inserted freely between said rolls and into contact with said gage and one of said rolls having a spiral feeding 65 portion for feeding stock against and across

said knife edge whereby said stock may be severed on a long diagonal scarf.

4. A feed mechanism comprising coöperating feed members acting at certain times to admit of stock being inserted freely therebetween, a gage arranged to be contacted by stock so inserted, and mechanism initiated by pressure of stock against said gage for actuating one of said feed members to feed said stock away from said gage. 75

5. A machine for scarving leather having, in combination, a fixed knife, a pair of work feeding elements arranged normally to permit movement of the work therebetween in a direction away from said knife, means 80 for actuating said feeding elements to grip the work and to move it toward said knife, and mechanism operating automatically upon movement of the work to a predetermined distance in the direction away from 85 said knife to initiate the operative movement of the feed elements.

6. A machine for scarving sheet material having, in combination, a pair of feed rolls, 90 a skiving knife mounted with its edge adjacent the bite of said rolls, said rolls being arranged normally to permit the insertion of material therebetween and in a direction away from said knife edge, a gage for determining the extent of such insertion, and 95 mechanism operative automatically upon contact of the material with said gage for initiating a movement of said rolls to grip and feed the material against the knife edge. 100

7. A feed mechanism comprising a pair 100 of feed rolls, one of said rolls having a cut-away portion whereby stock may be inserted freely between said rolls, a gage opposite the bite of said rolls, driving mechanism for said rolls, and control means for said mechanism actuable by said gage whereby pressure of stock against said gage actuates said mechanism to operate said rolls. 105

8. A skiving machine having, in combination, a pair of coöperating feed members, 110 a knife mounted with its edge adjacent the bite of said feed members, a gage element located upon the opposite side of said feed members from the knife, said gage being mounted for movement toward and from said feed members, actuating means for said feed members, and connections between said gage and actuating means whereby movement of said gage away from said feed members serves to initiate operative actuation 115 of the latter. 120

9. In a skiving machine, in combination, 125 a pair of coöperating feed rolls, a knife blade arranged with its edge adjacent the bite of the rolls, a support upon the opposite side of the rolls from the knife and adjustable toward and from the rolls, a gage element slidably carried by said support, resilient means urging said element toward said rolls, and mechanism actuable auto- 130

matically by movement of said gage element away from the rolls for initiating the feeding action of the latter.

10. In a machine of the class described, 5 operating mechanism, a gage, a driving mechanism, a clutch comprising a lug on said driving mechanism, a second lug on said operating mechanism normally projecting into the path of said first lug, a latch 10 for holding said second lug retracted out of

the path of said first lug, a third lug on said driving mechanism, means to retract said latch from its holding position, and a member arranged to be positioned by said gage between said means and said third lug 15 whereby said driving mechanism may act to retract said latch.

In testimony whereof I have signed my name to this specification.

JAMES H. REED.
